UNITED STATES PATENT OFFICE.

THOMAS F. MCGUIRE, OF BROOKLYN, NEW YORK, ASSIGNOR TO WILLIAM HOWARD FLEISCH, OF NEW YORK, N. Y.

CARBURETER.

1,183,019.

Specification of Letters Patent.

Patented May 16, 1916.

Application filed June 9, 1914. Serial No. 843,999.

To all whom it may concern:

Be it known that I, THOMAS F. MCGUIRE, a citizen of the United States, and residing in the borough of Brooklyn, county of Kings, 5 and State of New York, have invented certain new and useful Improvements in Carbureters, of which the following is a full and clear specification.

This invention relates to carbureters, and 10 has for its primary object to provide an improved construction for carbureters, in which the supply of fuel delivered into a mixing chamber is controlled by regulating the pressure in an auxiliary chamber through which 15 a portion of the fuel is passed on its way into the mixing chamber. In connection with said auxiliary chamber, means are provided for adjusting the pressures therein with respect to the pressures in the mixing chamber. 20

Another object is to provide a simple, efficient and durable construction whereby many of the troubles now met with in the use and adjustment of carbureters can be 25 readily overcome.

Another object is to provide an attachment of simple construction which can be installed in the mixing chambers of engines now in operation and by means of which 30 such engines can be much benefited.

Other and further objects will appear in the claims, and specification, reference being had to the accompanying drawing, in which,

35 Figure 1 is a longitudinal section of a carbureter provided with my improvements, parts being shown in elevation, and Fig. 2 is a transverse section of the same, parts being shown in elevation.

40 Referring more particularly to the drawings, the carbureter comprises a mixing chamber 1, with a depression in its lower wall 2 formed with an annular wall 3 within which is threaded a fuel inlet 4 provided 45 with an inlet opening 5 and a flange 6 which positions it within the annulus 3. The upper end of the inlet 4 is beveled to correspond with the form of the lower end of a tubular member 7, which is provided with a 50 nib 8 which depends into the inlet opening 5. The lower end of the tubular member 7 forms with the inlet 4 a conical passageway 9, leading from the inlet opening 5 into the mixing chamber. A variable pressure chamber 10 is provided within the upper end of

the tubular member 7, which communicates with the inlet opening 5 by way of a tubular passage 11 of relatively small diameter. A similar tubular passage 12 extends transversely through the tubular member 7, intersecting with the variable pressure chamber 10 and the tubular passage 11. Tubular member 7 is threaded into the upper wall 13 of the mixing chamber and is rotatable on its axis to vary the size of the passage 9. 60 For this purpose, the member 7 is provided with a flange 14, by means of which it may be turned. Adjacent the upper end of the variable pressure chamber 10 are air inlets 15, the inflow of air through which is regulated by a thumb screw 16. In the preferred embodiment shown in the drawings, the tubular member 7 extends vertically across the mixing chamber 1 and intermediately of a vertical branch 17 and a horizontal branch 75 18, either of which may be the end to be connected to the engine. A shutter valve 19 may be provided in the vertical branch and a similar shutter valve 20 may be provided in the horizontal branch for regulating the flow through said branches. A receptacle 21 for liquid fuel is connected to the carbureter, providing a float chamber in open communication with the inlet opening 5. A float 22 which operates a valve 23 relatively 80 to an inlet opening 24, serves to regulate the liquid level in the receptacle 21. As shown in Fig. 2, a resilient blade 26 is secured to the upper wall of the carbureter to press against the knurled flange 14 so as to retain 85 the member 7 in any position to which it may be adjusted. A similar resilient finger 27 is secured to the flange 14 and engages the thumb nut 25 on the upper end of screw 16. The operation of my improved carbureter 90 95 will now be understood and briefly described is as follows:

At lower speeds of the engine, the depression in the mixing chamber is not sufficient to cause the fuel to rise an appreciable 100 height in tubular passage 11 for the reason that the amount of air which passes through the variable pressure chamber 10 and into the mixing chamber 1 is relatively large. The fuel in this case is entirely supplied by 105 the main nozzle 9. However, as the speed increases, the suction of the engine increases, with the result that the pressure within the chamber 10 decreases. Eventually the fuel rising in tubular passage 11 reaches tubular 110

2
 passage 12, where it mixes with the air, coming from above and discharges into the mixing chamber through the transverse passage 12. The depression being considerably 5 greater in the mixing chamber 1 than in the chamber 10, fuel is drawn through the passage 12 into the chamber 1 and is atomized during the operation. The greater the degree of depression in the mixing chamber 1, 10 the greater will be the amount of fuel and air which is admitted into the mixing chamber through the passage 12. By means of this action, the so-called compensating valve which has been much used on carbureters, 15 can be eliminated, thus doing away with the inherent disadvantages of such compensating valves. These compensating valves which may be either spring or gravity operated, will remain inactive until gravity or 20 the spring pressure is entirely overcome, when they ordinarily open all at once and generally cause either an over-rich or too lean a mixture. In the device shown in the drawings on the other hand, a gradual increase 25 in fuel and auxiliary air is provided as the speed of the engine increases, so that a simple, efficient and automatic regulation of fuel and air is effected.

I claim:

- 30 1. In a carbureter, a mixing chamber provided with a fuel inlet, a tubular member projecting from a wall opposite to said fuel inlet and forming a passage between it and said fuel inlet, said tubular member forming 35 a variable pressure chamber and having a passage leading therefrom into said fuel inlet, an inlet channel extending from said variable pressure chamber into said mixing chamber, and means for adjusting the size 40 of the passage between said tubular member and fuel inlet.
2. In a carbureter, a mixing chamber provided with a fuel inlet, a hollow member within said mixing chamber constituting a 45 variable pressure chamber and having a passageway with an opening disposed opposite to said fuel inlet, said hollow member being adjustably mounted to vary the distance of said opening from the fuel inlet, and a passage extending between said variable pressure chamber and said mixing chamber, said hollow member being provided with an air inlet.
3. In a carbureter, a mixing chamber provided with inlet and outlet ports at opposite 50 ends thereof, a float chamber connected thereto by a fuel inlet, and a hollow air-containing member disposed across said mixing chamber between said inlet and outlet ports, said hollow member being provided with a port opening into said mixing chamber distant from said fuel inlet and a passage thereinto with an inlet for fuel disposed opposite to said fuel inlet.
4. In a carbureter, a mixing chamber provided with a fuel inlet in its lower wall, said fuel inlet being provided with a main nozzle, a variable pressure air chamber of relatively large cross section disposed above said fuel inlet and a vertically disposed fuel passage of relatively small diameter extending from said fuel inlet into said variable pressure chamber, said variable pressure chamber being provided with a port discharging directly into said mixing chamber.
5. In a carbureter, a mixing chamber provided with a fuel inlet projecting upwardly from its bottom wall, a tubular member depending from its upper wall and forming a passage between it and said fuel inlet, said tubular member having a variable pressure chamber, a passage leading therefrom into said fuel inlet, and an inlet channel extending from said variable pressure chamber into said mixing chamber, said tubular member being threaded into the upper wall of said mixing chamber and rotatable on its axis to adjust the size of the passageway between it and said fuel inlet.
6. In a carbureter, a mixing chamber provided with a fuel inlet projecting upwardly from its bottom wall, a tubular member depending from its upper wall and forming a passage between it and said fuel inlet, said tubular member having a variable pressure chamber, a passage leading therefrom into said fuel inlet, and an inlet channel extending from said variable pressure chamber into said mixing chamber, said variable pressure chamber having an inlet for air adjacent its upper end and means for regulating the size of the same, said tubular member being threaded into the upper wall of said mixing chamber and rotatable on its axis to adjust the size of the passageway between it and said fuel inlet.

THOMAS F. McGUIRE.
